CLAIM

The ornamental design for a public transit bench, as shown and described.

DESCRIPTION

FIG. 1 is a perspective view of one embodiment of a public transit bench illustrating my new design, the broken line showing of environmental structure being for illustrative purposes only and forming no part of the claimed design; FIG. 2 is a left side elevational view thereof, with the undisclosed right side elevational view being a mirror image of that illustrated;

FIG. 3 is a front elevational view thereof;

FIG. 4 is a rear elevational view thereof;

FIG. 5 is a top plan view thereof; and,

FIG. 6 is a bottom plan view thereof.
